UNITED STATES PATENT OFFICE.

FRANK H. ENGSTROM, OF CAMBRIDGE SPRINGS, PENNSYLVANIA.

COMBINATION-TOOL.

SPECIFICATION forming part of Letters Patent No. 677,964, dated July 9, 1901.

Application filed September 28, 1900. Serial No. 31,443. (No model.)

To all whom it may concern:

Be it known that I, FRANK H. ENGSTROM, a citizen of the United States, residing at Cambridge Springs, in the county of Crawford and State of Pennsylvania, have invented certain new and useful Improvements in Combination-Tools; and I do hereby declare the following to be a full, clear, and exact description of the invention, such as will enable others skilled in the art to which it appertains to make and use the same.

This invention relates to combination-tools; and it consists in the novel construction and combination of the parts hereinafter fully described and claimed.

In the drawings, Figure 1 is a plan view of the combination-tool. Fig. 2 is a side view of the same when closed. Fig. 3 is a cross-section taken on the line $\alpha\alpha$ in Fig. 1.

A is a scraper for cleaning the bushing of a valve both inside and outside. This scraper has notches b in its sides and beveled edges c at the bottoms of the said notches.

C is a spanner which is pivoted at one end to the scraper A by a pin or rivet d . This spanner is used for unscrewing the bushing of the valve. This spanner consists of two

arms having lateral projections e at their free ends. These projections e engage with the notches b when the instruments are closed together, and the beveled edges c at the bottoms of the notches permit the projections to be sprung out of engagement with the notches when the instruments are moved forcibly apart on their pivot-pin. When the instruments are closed together, they interlock and hold each other in the closed position.

What I claim is—

The combination, with a scraper having at one end lateral notches and beveled edges at the bottoms of the said notches, of a spanner pivoted to the other end portion of the scraper and comprising two spring-arms provided with projections which engage with the said notches when sprung over the said beveled edges so as to straddle them, substantially as set forth.

In testimony whereof I affix my signature in presence of two witnesses.

FRANK H. ENGSTROM.
